UNITED STATES PATENT OFFICE.

ALBERT RUSH, OF COLUMBUS, OHIO.

DOOR FOR ELEVATOR-SHAFTS.

1,341,864.

Specification of Letters Patent.

Patented June 1, 1920.

Application filed October 9, 1919. Serial No. 329,499.

To all whom it may concern:

Be it known that I, ALBERT RUSH, a citizen of the United States, residing at Columbus, in the county of Franklin and State of 5 Ohio, have invented a certain new and useful Improvement in Doors for Elevator-Shafts, of which the following is a specification.

This invention relates to the type of door 10 for elevator shafts shown and described in the Letters Patent of the United States issued to me September 9, 1919, No. 1,315,795, said type being characterized by the feature, among others, that the door can be made of 15 full height and raised and lowered and supported when raised by means on the top of the car.

The object of the present invention is a modification including special means where- 20 by vertical guides on the car which permit the car to pass a door without its operation may be utilized to deflect the door when raised away from the doorway wall above the doorway and conversely toward its door- 25 way closing position when lowered.

The invention is embodied in the example herein shown and described, the features of novelty being finally claimed.

In the accompanying drawings—

30 Figure 1 is a vertical sectional view through the doorway wall of an elevator shaft showing my invention applied thereto, the door being in its lowered position.

Fig. 2 is a similar view showing the door 35 raised.

Fig. 3 is a horizontal section on a slightly larger scale on the line III—III Fig. 1, looking down.

40 Fig. 4 is a similar section on the line IV—IV Fig. 1 also looking down.

In the views 5 designates the doorway wall of the building having at the floors thereof opening 6 with sill 6^a. The character 7 designates a door having connected 45 therewith chains or flexible members 8 provided with weights 9, the chains passing over pulleys 10 journaled on the opposite sides of the elevator shaft in position to pull the upper end of the door toward the 50 center of the well. At its upper end the door has pivoted to its opposite upper corners arms 11 provided with inwardly projecting lateral studs 11^a, and at the opposite lower corners arms 12 provided with lateral 55 studs 12^a. The studs 11^a and 12^a project into

vertically arranged channels 13 secured to the opposite sides of the car or carriage 14. These channels extend above the top of the car where they are braced by bars 13^a. The outer or building side of the door is provided with hooks 15 that, when the door is lowered, take into sockets 16 in the doorway wall at opposite sides of the doorway to hold the door from facewise movement when closed. 60

The opposite side walls of the elevator shaft are provided with stops 17 against which outward lateral projections 11^b on the arms 11 abut when the door nearly approaches its closing position thus arresting the motion of those ends of the arms 11 that travel in the guides or channels 13 without arresting their pivoted ends thereby causing said arms to deflect the door toward closed position, as shown in Fig. 1. The gravity of 70 the door, or a force applied to it in closing the same, causes the arms 11 to assume or approach horizontal position, as shown in Fig. 1, to close the door. The rigid arms 12 with the studs 12^a serve as fulcrums upon which 75 the upper portion of the door is deflected inward when the door is raised. It will be observed that by reason of this construction the door can be raised past the projecting sill of the doorway next above and the edge 80 of said sill made to nearly coincide with the floor of the car so as to leave no considerable gap between them. 85

The door can be raised and lowered by hand or by other suitable power applied 90 thereto.

When the door is closed the car moves past the same without, in any way, affecting the same, the channels of guides 13 traveling past the studs 11^a and 12^a. 95

The forms of the parts can be changed without departing from the gist of the invention as claimed.

What I claim is:

1. In a building having an elevator shaft, 100 doorways leading thereto and a car to move in said shaft, the combination of a door, a guide on the car projecting above the top of the car, hinging means connecting the upper portion of the door with said guide, 105 rigid means connecting the lower portion of the door with said guide and means whereby said upper hinging means may be deflected to cause the deflection of the upper portion of the door when raised. 110

2. In a building having an elevator shaft, doorways leading thereto and a car to move in said shaft, the combination of a door, a vertical guide on the car, hinging means connecting the upper portion of the door with said guide, rigid means connecting the lower portion of the door with said guide, and means whereby said upper hinging means may be deflected to cause the deflection of the upper portion of the door when raised.

3. In a building having an elevator shaft, doorways leading thereto, doors for the doorways and a car to move in said shaft, the combination of a door guide on the car projecting above the top of the car, hinging means connecting the upper portion of a door with said guide, rigid means connecting the lower portion of the door with said guide, means whereby said upper hinging means may be deflected to cause the deflection of the upper portion of the door when raised, and means for arresting one end of said hinging means when the door ap-

proaches closing position to cause the closing of the door.

4. The combination with a building having an elevator shaft, a doorway leading from a floor of the building to the shaft, and a car to move in said shaft, of an upwardly sliding door for the doorway, a guide for the door, hinged means connecting the door with the guide and a fixed stop to arrest said hinged means when said door approaches closing position to cause facewise movement of the door to close the same.

5. In a building having an elevator shaft, doorways leading thereto and a car to move in said shaft, the combination of a door, a guide on the car, hinging means connecting the upper portion of the door with said guide, rigid means connecting the lower portion of the door with said guide and means whereby said upper hinging means may be deflected to cause the deflection of the upper portion of the door when raised.

ALBERT RUSH.
